(57) **CLAIM**

The ornamental design for a display screen or portion thereof with animated graphical user interface for quantitative trading, as shown and described.

DESCRIPTION

FIG. 1 is a first image of a front view of a display screen or portion thereof with animated graphical user interface for quantitative trading showing a first image in the sequence showing our new design;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is an eighth image thereof;

FIG. 9 is a ninth image thereof; and,

FIG. 10 is a tenth image thereof.

The long dash-short dash lines indicate the boundary of the display screen. The short dash-short dash lines and broken text illustrate text areas, text, or graphical features that form no part of the claimed design. The appearance of the animated images sequentially transitions between the images shown in FIGS. 1-10. The process or period in which one image transitions to another forms no part of the claimed design.
